UNITED STATES PATENT OFFICE.

AARON J. TYLER, OF ROCHESTER, NEW YORK.

VALVE.

1,035,398.

Specification of Letters Patent. Patented Aug. 13, 1912.

Application filed March 17, 1909. Serial No. 484,050.

To all whom it may concern:

Be it known that I, AARON J. TYLER, citizen of the United States, residing at Rochester, in the county of Monroe and State of New York, have invented certain new and useful Improvements in Valves, of which the following is a specification.

This invention relates to valves and more particularly to a valve or stop cock especially designed for use in curb boxes for controlling the flow of water, gas or other fluid from the city main to the service pipe.

It is a well known fact that a slight tap or downward pressure imparted to the turning plugs or stop cocks, as at present constructed, causes the plug to wedge at its seat, with the result that the plug must be driven back before the same can be operated to control the flow of fluid through the valve casing. This wedging or jamming of the plug in its seat invariably causes leakage and necessitates re-grinding of the plug to insure a tight joint between the parts. Moreover, where the stop cocks are positioned in curb boxes and similar inaccessible places, it is evident that considerable labor and expense is attendant upon the removal of the plug to effect necessary repairs thereto. Considerable trouble has also been experienced in retaining the stop cock in proper position to be engaged by a wrench or other tool, when it is desired to operate the same, this displacement of the stop cock being due to the tendency of the latter to tilt or turn in the curb box.

The object of the invention is to obviate the above defects and to provide a strong, durable and thoroughly efficient stop cock in which liability of the turning plug jamming or wedging in its seat is positively eliminated.

A further object of the invention is to provide the valve casing with laterally extending pins or trunnions adapted to enter correspondingly shaped openings in the curb box, thereby to support the valve in the box and retain the head of the plug in position to be engaged by the operating key at all times.

50 A still further object of the invention is generally to improve this class of devices

so as to increase their utility, durability, and efficiency.

Further objects and advantages will appear in the following description, it being understood that various changes in form, proportions, and minor details of construction may be resorted to within the scope of the appended claims.

For a full understanding of the invention and the merits thereof and also to acquire a knowledge of the details of construction and the means for effecting the result, reference is to be had to the following description and accompanying drawings, in which:

Figure 1 is a vertical section view of a stop cock constructed in accordance with my invention; Fig. 2 is a horizontal sectional view of the same; Fig. 3 is a side elevation; Fig. 4 is a top plan view; Fig. 5 is a side elevation of the turning plug detached, a top plan and a bottom plan of the turning valve being shown immediately above and below the same; Fig. 6 is a similar view looking at the ported side of the plug; Fig. 7 shows a bottom plan, top plan, side elevation, and sectional view respectively, of the locking nut; Fig. 8 represents a top plan, transverse section and side elevation of the stop washer detached; Fig. 9 represents a side elevation and top plan view of the lower compensating washer.

Corresponding and like parts are referred to in the following description and indicated in all the views of the drawings by the same reference characters.

The improved turning plug forming the subject matter of the present invention comprises a valve casing 5 having oppositely disposed nipples 6, the interior walls of which are threaded at 7 for engagement with the correspondingly threaded ends of a liquid or fluid conducting pipe.

The valve casing 5 is provided with a tapered seat 8 in which is mounted for rotation a correspondingly tapered turning plug 9, the latter being preferably hollow, as shown, and provided with oppositely disposed ports 10 adapted to register with the ports 11 in the valve casing, thereby to permit the passage of water or other fluid through said valve casing.

The upper or large end of the valve is provided with an extension or head 12, preferably of angular formation, as shown, and having its angular walls slightly tapered for engagement with the correspondingly tapered walls of a key or similar tool employed for rotating the plug. Extending transversely across the top of the head 12, is a rib 13 which centers the key or operating tool with respect to the turning plug and also serves to indicate to the operator the position of the valve so that the operator can readily ascertain whether the water or other fluid is turned off or on. The side walls of the head 12 are also preferably inclined or curved laterally at 14 to assist in guiding the tool on the head and also to form abutments for the tool, thereby to limit the downward movement of said tool.

The upper end of the valve, immediately below the head 12, is provided with exterior threads 15 for engagement with a correspondingly threaded clamping nut 16, the latter being adapted to bear against a washer 17 interposed between the lower face of the nut and the upper face or stop shoulder 18 of the valve casing, as best shown in Fig. 1 of the drawings. The washer 17 by engagement with the nut 16, serves to limit the downward movement of the turning plug 9 and thus prevent wedging or jamming of the turning plug in its seat when a slight tap or longitudinal pressure is exerted on the head 12, as for instance, when positioning the operating tool thereon.

Attention is here called to the fact that the lower face of the clamping nut 16 is spaced vertically from the annular shoulder 19 on the turning plug so as to permit a limited vertical movement of the turning plug within its seat, thereby to assist in alining the ports 10 and 11 and also to insure the proper seating of the plug within the valve casing.

The lower end of the turning plug 9 is provided with a reduced portion 20 terminating in a threaded extension 21 for engagement with a correspondingly threaded nut 22. The walls of the seat 8 between the base of the reduced portion 20 and the lower end of the valve casing, are preferably disposed parallel with each other for engagement with an annular boss or flange 23 of a lower washer, indicated at 24. The lower washer 24 is interposed between the nut 22 and the adjacent end of the valve casing and is adapted to bear against said valve casing when the nut 22 is adjusted, thereby to hold the turning plug firmly to its seat and effectually prevent leakage between the parts. The interior walls of the nipples 6 at the ports 11, are preferably enlarged as shown at 25, in order to form a clearance and thus facilitate the flow of water through the valve casing when the turning plug is 65 in open position.

Secured to or formed integral with the opposite sides of the valve casing, are bosses or enlargements 26 having trunnions 27 extending laterally therefrom and provided with exterior threads 28 for engagement with correspondingly threaded nuts 29, said pins or trunnions being adapted to enter correspondingly shaped openings formed in the adjacent walls of a curb box, when the 75 valve is used in this connection, and thus assist in supporting the valve so as to prevent tilting or turning movement of the latter within the curb box. When the valve is positioned in a curb box, the nuts 29 will 80 bear against the exterior walls of the curb box and clamp the valve casing within the same, so as to retain the head 12 of the turning plug in proper position to be engaged by the key or operating tool at all times. 85 The trunnions 27 also permit the valve casing to be tilted or turned slightly when necessary to properly aline the same, the valve casing being locked in rigid position by adjusting the nuts 29. If desired however, 90 the trunnions and clamping nuts may be dispensed with, or a single trunnion may be employed for supporting the valve casing within the curb box, and in some cases, either one or both trunnions may be utilized 95 for supporting the valve casing without the employment of either nut.

The transverse rib 13 may be in the form shown in Fig. 4 of the drawings, that is to say, with its intermediate portion provided 100 with a circular enlargement 30, or of the construction shown in Fig. 6 of the drawings, in which the opposite walls of the rib are substantially parallel throughout the entire length thereof.

The turning plug 9 is preferably formed with oppositely disposed flat portions 26' for engagement with correspondingly flat portions 27' formed on the washer 17, thereby to lock the washer on the valve and thus 110 cause the two to turn together when the valve is moved to open and closed positions. Thus it will be seen that the impact of a tap or blow imparted to the head 12 will be received upon the washer 17, which in turn 115 bears against the upper end of the valve casing so as to effectually prevent wedging or jamming of the valve in its seat and thus insure perfect operation of the valve under all conditions, the trunnions 27 serving to 120 assist in supporting the valve and maintaining the head of the turning plug in proper position to be engaged by an operating tool, as before stated.

While the valve is described in connection 125 with a curb box, it will of course be understood that its range of usefulness is not limited to curb boxes, but that the same may be

used with equally good results for controlling the flow of fluid through all kinds of conductors and for other purposes without departing from the spirit of the invention.

5 Having thus described the invention, what is claimed as new is:

1. A valve including a casing having a tapered valve seat, a tapered valve engaging the seat, and means carried by the large end 10 of the valve to engage the casing immediately adjacent the valve seat for preventing wedging of the valve in its seat, said means being actuated to adjust the valve to its seat without removing the valve from the casing 15 and being movable with the valve.

2. A valve including a casing having a tapered valve seat, a tapered valve engaging the seat, a nut carried by the large end of the valve, and means interposed between the 20 nut and valve casing immediately adjacent the valve and the valve seat for preventing wedging of the valve in its seat, said means being actuated to adjust the valve to its seat without removing the valve from the casing 25 and being movable with the valve.

3. A valve including a casing having a tapered valve seat and provided with a plane upper face around the valve seat, a tapered valve engaging the seat, a nut carried by 30 the large end of the valve, and a washer interposed between the nut and upper end of the valve casing and having a plane under face bearing upon the plane upper face of the casing for preventing wedging of the 35 valve in its seat, said washer being actuated to adjust the valve to its seat without removing the valve from the casing and being movable with the valve.

4. A valve including a casing having a 40 tapered valve seat and a plane upper end, a tapered valve engaging the seat and having its intermediate portion exteriorly threaded, a nut engaging the threaded portion of the valve at the large end thereof, 45 and a washer having a plane under face and interposed between the nut and the plane upper end of the valve casing for preventing wedging of the valve in its seat, said washer being actuated to adjust the valve 50 to its seat without removing the valve from the casing and being movable with the valve.

5. A valve including a casing having a tapered valve seat, a tapered valve engaging the seat and provided with a flat portion, a 55 clamping nut threaded on the large end of the valve, and a washer interposed between the clamping nut and valve casing and having a correspondingly flat portion for engagement with the flat portion of the valve, 60 said washer serving to prevent wedging of the valve in its seat and being actuated to adjust the valve to its seat without removing said valve from the casing.

6. A valve including a casing having a

tapered valve seat, a correspondingly shaped 65 valve engaging the seat and having its large end provided with a head, the top of which is provided with a transverse rib, a nut threaded on the valve at the large end thereof, and a washer movable with the 70 valve and interposed between the nut and valve casing, said washer being actuated to adjust the valve to its seat without removing the valve from the casing.

7. A valve including a casing having a 75 tapered valve seat, a valve engaging the seat and provided with a terminal tapered head, there being threads formed on the valve below the head, a clamping nut engaging said threads, and a washer interposed between 80 the nut and casing and mounted for rotation with the valve for preventing wedging of the valve in its seat, said washer being actuated to adjust the valve to its seat without removing the valve from the casing.

8. A valve including a casing having a tapered seat, the walls of which are disposed parallel for a portion of the length of said seat, a correspondingly tapered valve engaging the seat and having its upper end threaded and provided with a terminal head of angular formation, a clamping nut threaded on the valve beneath the head thereof, a washer interposed between the clamping nut and upper end of the valve casing and 95 mounted for rotation with the valve, means carried by the lower end of the valve for preventing withdrawal of the latter, and a washer interposed between the retaining means and the lower end of the casing and 100 provided with a laterally extending boss adapted to bear against the parallel walls of the valve seat.

9. A valve including a casing having oppositely disposed trunnions for attachment 105 to a support and provided with a valve seat, and a valve engaging said seat.

10. A valve including a casing having oppositely disposed threaded trunnions for engagement with a support and provided 110 with a valve seat, a valve engaging the seat, and clamping nuts threaded on said trunnions and adapted to engage the support for preventing tilting movement of said valve casing with respect to the support.

11. A valve including a casing having oppositely disposed trunnions, the terminals of which are threaded, said casing being provided with a valve seat, a valve engaging said seat, means for preventing wedging 120 of the valve within the seat, and clamping nuts threaded on the trunnions and adapted to bear against a support for preventing turning movement of the valve with relation to said support.

12. A valve having a valve casing and provided with a laterally extending trunnion for engagement with a support, a valve

engaging the seat and provided with a threaded portion terminating in an angularly disposed head, a clamping nut engaging the threads on the valve, and a washer interposed between the clamping nut and adjacent end of the valve casing for preventing wedging of the valve in its seat.

In testimony whereof I affix my signature in presence of two witnesses.
